US0D1064634S

(12) United States Design Patent (10) Patent No.: US D1,064,634 S
(45) Date of Patent: * Mar. 4, 2025

(54) GAMING CHAIR FOR ELECTRONIC GAMES STATIONS

(71) Applicant: GT Omega Racing Ltd, Renfrewshire (GB)

(72) Inventor: Shengduan Li, Foshan (CN)

(73) Assignee: GT Omega Racing Ltd, Paisley (GB)

() Term: 15 Years

(21) Appl. No.: 35/515,658

(22) Filed: Aug. 8, 2022

(80) Hague Agreement Data

Int. Filing Date: Aug. 8, 2022

Int. Reg. No.: DM/224819

Int. Reg. Date: Aug. 8, 2022

Int. Reg. Pub. Date: Nov. 25, 2022

(30) Foreign Application Priority Data

Feb. 9, 2022 (CN) 202230065324.9
